(57) **CLAIM**

The ornamental design for a notebook computer, as shown and described.

DESCRIPTION

FIG. 1 is a perspective view of a notebook computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 shows a first operating state of the notebook computer of FIG. 1;

FIG. 9 shows a second operating state of the notebook computer of FIG. 1; and,

FIG. 10 shows a third operating state of the notebook computer of FIG. 1.

Broken lines are for illustrative purposes only and form no part of the claimed design.
